UNITED STATES PATENT OFFICE.

WILLIAM A. SCHLEICHER, OF CLEVELAND, OHIO.

DESIGN FOR A BUCKLE.

SPECIFICATION forming part of Design No. 32,776, dated June 5, 1900.

Application filed April 19, 1900. Serial No. 13,543. Term of patent 14 years.

To all whom it may concern:

Be it known that I, WILLIAM A. SCHLEICHER, a citizen of the United States, residing at Cleveland, in the county of Cuyahoga and State of Ohio, have invented and produced a new and original Design for Buckles, of which the following is a full, clear, and exact specification, reference being had to the accompanying drawings, forming a part of this specification.

In the drawings, Figure 1 is a perspective view of a harness-buckle embodying my design; Fig. 2, a plan view, and Fig. 3 a longitudinal central section thereof.

This invention relates to designs for buckles for use in connection with straps, such as harness-straps, particularly where it is desired to removably secure snap-hooks and other appliances to straps and for other uses of a similar character.

My new design consists in a buckle having the shape and configuration substantially as shown in the drawings and as hereinafter described.

As shown in the drawings, a buckle embodying my new design consists of a substantially-rectangular frame A, having longitudinal side bars *a a*, which side bars have substantially-flat outer and inner surfaces *a' a'* and which are connected by the three cross-bars—viz., the flat horizontal rear bar *b*, the forward bar *c*, and the middle bar *d*. As shown, the rear bar *b* and the forward bar *c* extend across the upper portion of the buckle-frame, while the middle bar extends across the bottom of the same. At the forward end the buckle-frame A terminates in a substantially-flat tongue E, which is somewhat reduced in width and curved backward

at its extremity so as to form a beak or hook *e*. The upper and lower edges *a³ a⁴* of the side bars *a a* are each of a slightly-curved continuous almost straight contour; but at their rear ends they are bent upward to form

substantially-concentric arcs *a⁵* until they meet and merge in the horizontal rear bar *b*, whose upper surface is slightly curved and whose forward edge is provided with a lip *b'*, extending into the rectangular space between

the bars *b* and *c*. At the forward portions *a⁶*, where the forward bar *c* extends across the side bars *a a*, are also raised forming arc-shaped projections, which meet and merge in the cross-bar *c*, whose upper surface is

transversely curved on substantially the same 55 arc, as shown. The cross-bars *b* and *c* are substantially in the same horizontal plane. The middle bar *d*, which connects the lower edges of the side bars *a a*, is substantially 60 parallel to the plane of the cross-bars *b* and *c*, and its upper surface is slightly curved transversely to its length, as shown. It is provided with the strap-retaining stud *d'*.

The forward tongue *E*, as shown, is bent downward somewhat, thus forming an angle at 65 *e'* with respect to the side bars *a a*, which side bars, as seen in Fig. 3, are tapered forwardly at *a⁷* until they merge in the tongue *E*. The said tongue, as seen from Fig. 2, is somewhat reduced in width, its outer edges *e²* being 70 substantially in line with the inner faces *a²* of the side bars *a a*. The tongue *E* is, moreover, provided with a substantially-rectangular recess *e³*, whose corners are somewhat 75 rounded, as are also the corners of the end of the tongue *E*, the beak *c*, and other parts of the buckle. The recess *e³* is considerably larger in area than the beak *e*, so that when looking down on the buckle a U-shaped opening is exposed to view, as will be understood 80 by reference to Fig. 2.

The essential features of my design are the slightly and continuously curved side bars in combination with the cross-bars *b*, *c*, and *d*, arranged as shown, the cross-bar *b* being 85 provided with an inwardly-extending lip *b'*, all of the cross-bars having their upper surfaces somewhat curved in a direction transverse to their length. The substantially-rectangular form of all of the horizontal contours of the buckle, including the openings or recesses and the beak, also enters into my 90 design as an important feature.

A buckle so designed, particularly when applied to a strap, has a very pleasing and 95 harmonious effect by reason of its simple and chaste contours.

What I claim, and desire to secure by Letters Patent, is—

The design for a buckle substantially as 100 herein shown and described.

In testimony whereof I affix my signature in presence of two witnesses.

WILLIAM A. SCHLEICHER.
